UNITED STATES PATENT OFFICE.

ARTHUR TOFANI, OF PHILADELPHIA, PENNSYLVANIA.

FOLDING SHIFTABLE TABLE-TOP.

1,367,216.

Specification of Letters Patent.

Patented Feb. 1, 1921.

Application filed February 18, 1920. Serial No. 359,743.

To all whom it may concern:

Be it known that I, ARTHUR TOFANI, a subject of the King of Italy, (but who have declared my intention of becoming a citizen of the United States,) and now residing at the city of Philadelphia, in the county of Philadelphia and State of Pennsylvania, have invented certain new and useful Improvements in Folding Shiftable Table-Tops, of which the following is a specification.

My invention relates to a table having a shiftable member and a folding member arranged to be automatically locked in whatever shifted position is given the same.

The principal object of my invention is to provide a table having a shiftable member and a folding member foldable either onto the shiftable member or arranged for being permitted to be extended therefrom in a plane of the shiftable member, for forming either an oblong or rectangular-shaped table top and the arrangement being such as that one member becomes automatically locked the instant the shifted position is determined of one of the members of the said table top.

The nature, scope and characteristic features of my invention will be more fully understood from the following description taken in connection with the accompanying drawings forming part hereof, in which—

Figure 1 is a top or plan view of the table top, embodying the main essential features of my invention, with one of the hinged members of the table top folded onto the other member thereof, to provide an oblong-shaped table top.

Fig. 2 is a side view of the table top, showing the automatic locking contrivance for holding the fulcrumed folding member of the table top in whatever shifted position given the same.

Fig. 3 is a top or plan view of the two hinged members of the table top, in extended position, to thereby provide a substantially rectangular-shaped top in a locked position.

Fig. 4 is a fragmentary end view of the table top.

Fig. 5 is an underneath plan view of the table top, showing the locking-means in a preferred form, for automatically locking the shiftable members of the table top, and

which means is adapted to manually release the top in whatever position given the same and after the shiftable member is to be given another ultimate form, for example, from that of an oblong single leaf top to that of a rectangular-shaped top; and

Fig. 6 is a detailed view of the locking-means for the said table top.

Referring to the drawings, *a*, represents the framing with four legs constituting the table. On the under side, as shown in Fig. 5 is arranged a cross strip *a*¹, to which is fulcrumed at *b*, the shiftable member of the table top *c*, to assume either an oblong form or a rectangular-shape. The member *c*, has hinged thereto at *c*¹, a complementary member *c*², for permitting of extension of the table top through first shifting the member *c*, on its fulcrum *b*, to form thereby through the outfolding of the member *c*², a substantially rectangular-shaped table top, as clearly illustrated in Fig. 3. In opposite sides of the framing *a*, of the table, diagonally positioned with respect to each other, are located apertures *d* and *d*¹. A locking-means *e*, is located in the rear of the said apertures and consists of a substantially U-shaped spring *e*¹, which is formed into a coil at *e*², which latter is engaged by a post *e*³. Within the apertures *d* and *d*¹, the said spring *e*¹, is formed into an offset *e*⁴, to bear against a cross-pin *e*⁵, and thereby to more or less position the same, in operative relation within the said apertures. Beyond the said pin the said spring *e*¹, is formed into an eye *e*⁶, for engaging a finger therewith to manually manipulate the same, for the release of the table top member *c*, previously shifted on its fulcrum *b*, to become automatically locked in the position given the same, as for example, as illustrated in either Fig. 1 or 3; and which firmly holds the same, until manually released from such position by the manipulation through a finger of the eye *e*⁶, to permit of the said member being shifted either into the condition of the table top, as illustrated in Fig. 1 or in Fig. 3, of the drawings.

Having thus described the nature and objects of my invention, what I claim as new and desire to secure by Letters Patent is:

A foldable top table having side frames provided with slots and a locking device located in rear of each slot, said locking-

means formed at one end into a coil and said means extending through said slot and therein formed into an offset for becoming engaged by a pin of said slot for positioning the same and beyond said slot formed into a finger-hold for releasing said means from the locked condition of the table top, substantially as described.

In witness whereof, I have hereunto set my signature in the presence of two subscribing witnesses.

ARTHUR TOFANI.

Witnesses:

J. WALTER DOUGLASS,
PATRY TOFANI.
